UNITED STATES PATENT OFFICE.

THOMAS A. GLENDINNING, OF NEW YORK, N. Y.

TEMPORARY BINDER.

SPECIFICATION forming part of Letters Patent No. 774,516, dated November 8, 1904.

Application filed June 22, 1903. Serial No. 162,491. (No model.)

To all whom it may concern:

Be it known that I, THOMAS A. GLENDINNING, a citizen of the United States, residing in Manhattan borough, city of New York, in the county of New York and State of New York, have invented certain new and useful Improvements in Temporary Binders, of which the following is a specification.

This invention relates to means for temporarily binding or otherwise holding a set of papers, leaves, cards, or the like; and its principal object is to prevent the temporary binder or holder from being tampered with and one or more papers, sheets, cards, or the like removed or inserted without the knowledge of the one in charge of the binder.

To this end I contrive means whereby the device which binds or holds the leaves or other devices may be operated only by a specially-fitted key, so that when the leaves are clamped and the key removed it is difficult or impossible to operate the mechanism for the purpose of removing or inserting a leaf, except by one having a special key, it being intended that each of the binders made according to my invention shall have individual keys, the keys of each binder different from the keys of the others.

In the drawings forming part of this specification, Figure 1 is an end view of a temporary binder having my improvements applied thereto. Fig. 2 is a view at one end of the binder, showing the preferred connection between the key-cylinder and the leaf-binding rod. Fig. 3 is a section taken on line $x-x$ of Fig. 7. Fig. 4 is a fragment of a leaf, showing one of its openings, whereby it is impaled upon a series of rods used in the binder. Fig. 5 is a perspective view of a connector seen at Fig. 2. Fig. 6 is a perspective view of a housing for the key-cylinder and its locking-tumblers; and Fig. 7 is a general view of a temporary binder having my improvements applied thereto and shown partly in section, the leaves being removed.

In the several views like signs denote like parts.

The binder illustrated in this instance comprises a back or framework 1, having at its ends flanges 2 and 3, between which extend

longitudinal clamps 4 and 5 for binding the sheets or leaves 6, said clamps 4 and 5 being formed upon the edges of longitudinal cheek-pieces 7 and 8, respectively, which curve within the main frame or back 1 of the binder, as seen at Fig. 3, and at their ends are provided with inwardly-projecting guide extensions 9 and 10, which work between said back 1 and guide-plates 11 and 12, attached to the back at its extremities by rivets 13, as seen at the right hand of Fig. 7. The clamps may thus be moved toward or away from each other in said guiding means for accommodating thin or thick packs of leaves.

A central rod 15 extends longitudinally of the clamping-jaws 4 and 5 and is provided at its ends with right and left screw-threads 16 and 17, the threaded portions of the rod being engaged by nuts 18 and 19, respectively, each nut being connected by links 20 to the opposite clamping-jaws, so that upon revolution of the rod the nuts are moved simultaneously either toward the end of the rod or else toward the middle portion thereof, the action of the links 20 being to open or close the clamping-jaws 4 and 5. Said threaded rod is rotatably mounted in bearings 21 and 22, provided upon the frame at the central portion of the binder, and is provided with a collar 23 confined between said bearings, whereby endwise play of the rod is prevented. The frame is provided with ribs 24, one on each side of the rod, for guiding the nuts 18 and 19, each of which has a portion 25 protruding between said ribs, as seen at Fig. 3.

Upon one end of the rod is provided a collar 26, having a lug 27, and at this end of the rod is provided a cylinder 28, having a lug 29 for co-operation with the lug 27. Said cylinder is mounted within a housing 30, having a lateral extension 31, which is secured by a screw 32 or otherwise upon fixed plate 12. Said cylinder extends through said housing, having at its inner end a cap 33 and at its outer end a head 34, whereby longitudinal displacement is prevented. The lug 29 is preferably formed upon said cap 33. In said cylinder is an irregular keyhole 35, in which is removably fitted a key 36, said key being shown in cross-section at Fig. 1 and being adapted to turn

the cylinder to an unlimited extent, whereby by the coöperation of the lug 29 with the lug 27 the rod 15 is turned for either binding or releasing the jaws 4 and 5. Within the cylinder are provided pin-tumblers 37, and within the extension 31 of the housing are mounted coöperative pin-tumblers 38, operated by compression-springs 39, said tumblers being released by the key 36, so as to permit rotation of the cylinder to effect the turning of the rod 15. At Fig. 7 the tumblers are shown in their released positions; but it will be understood that when the key is withdrawn the springs 39 press the tumblers 38 into the tumbler-holes 40 in the cylinder, so as to lock the same, whereby removal of the sheets 6 when they are once clamped by the jaws 4 and 5 is prevented, as is also the insertion of new sheets. The tumblers are intended to be differently arranged in different binders, so that each requires its individual specially-fitted key.

If the lug 27 is in a position to come directly in contact with the lug 29 after the key 25 has rotated the screw-shaft in one direction a sufficient amount—as, for instance, to bind or clamp the leaves in position—a point may be reached where the key cannot be turned farther in that direction and that the key will 30 be at a position where it will be impossible, owing to the organization of the class of lock which is employed, to withdraw the key from the lock. Consequently the key must be turned backward until it comes to the position where 35 it may be withdrawn. This organization of lugs permits the key to turn backward nearly a complete revolution; but there are instances where the key may turn the screw up to the point at which it is desired to be left, but at 40 such a position that to turn the key back to its point of removal would slightly loosen the clamping action upon the sheets. In many instances (and, in fact, generally) a slight loosening or tightening, as the case may be, to 45 bring the key to this particular position would not interfere with the proper action of the device; but there are instances and certain employments where it will be found necessary to avoid this feature, and means for so 50 doing are illustrated in Figs. 2 and 5. Fig. 5 shows a connector in the form of a tumbler organized to admit a greater amount of idle movement than that of the organization previously described and is shown as comprising 55 a body 44, bored at 45 to fit upon an extension 46 of the screw-rod 15 and having lugs 47 and 48, the former to engage the lug 29 of the cylinder and the latter to engage the lug 27 of the screw-rod. The connector is introduced, so as to increase the range of rotation 60 of the cylinder independently of the screw-rod, so that the said cylinder can be turned more than one revolution independently, thus insuring the ready release of the key from the 65 cylinder after clamping the sheets or leaves.

Telescoping rods 49 and 50 are provided between the clamps 4 and 5, and each leaf is preferably provided with a key-slot 51, Fig. 4, to facilitate impaling upon and removal from said rods.

Variations may be resorted to within the scope of my invention, and portions of my improvements may be used without others. My invention may be applied to other devices than temporary binders, and many variations in the forms of the special keys and keyholes and wards and tumblers may be resorted to within the scope of my improvements, so long as each binder or the like is provided with its own special key, which may be operated to lock or secure its leaves, but is not adapted to fit the keyholes of other similar binders or holders. Both ends of the binder may be formed, as shown at Fig. 2, so that it is necessary to employ two keys, one fitted to each cylinder, to release the binding mechanism, so that so long as both keys are in place either key may be turned to effect the rotation of the threaded rod. The keys may be different one from the other, so that each can release only the lock to which it is specially fitted, and when the keys are in the possession of different persons both must be present in order to enable a leaf to be removed, thereby increasing the security afforded by locking the leaf-binding mechanism. Other tumbler-locks than that herein illustrated may be used, and so long as tumblers are used in such a way that only the person in charge is able to unclamp the leaves the structure is 100 within the scope of my invention.

Having thus described my invention, I claim—

1. The combination with means to releasably hold a set of leaves or the like, including a member to secure the leaves, of means to effect movement of said securing means and embodying key-controlled tumblers, and a connecting-tumbler having an amount of idle movement.

2. The combination with means for holding a set of leaves or the like, including a threaded rod and means connected thereto for releasably securing the leaves, of a cylinder mounted for rotation; a lug upon said cylinder; a lug upon said rod; connecting means between said lugs; an irregular keyhole in the end of said cylinder; a key removably fitted in said keyhole; and a tumbler released by said key.

3. The combination with means for holding a set of leaves or the like, including a threaded rod and means connected thereto for releasably securing the leaves, of a cylinder mounted for rotation; a lug upon said cylinder; a lug upon said rod and adapted to be rotated by the former lug; an irregular keyhole in the end of said cylinder; and a key removably fitted in said keyhole.

4. The combination of a pair of clamps,

transverse telescopic rods extending between them, a rod threaded right hand at one end and left hand at the other end and extending longitudinally of said clamps, nuts upon the 5 threaded portions of said rod, opposite links connecting said nuts to said clamps, a cylinder mounted at the end of said rod and having a lug, a lug upon the end of said rod adapted to be rotated by said former lug, a housing in 10 which said cylinder is mounted, pin-tumblers also mounted in said housing at one side of said cylinder so as to clear the leaves impaled upon said transverse telescopic rods, and a key removably fitted in said cylinder for releasing 15 said tumblers and turning said cylinder.

5. The combination of a frame, a guide at each end thereof, transverse telescopic rods extending between them, a rod threaded right 20 hand at one end and left hand at the other end and extending longitudinally of said clamps, nuts upon the threaded portions of said rod, links connecting said nuts to said clamps, a cylinder mounted at the end of said rod and 25 having a cap and a lug upon said cap, a lug upon the end of said rod adapted to be rotated by said former lug, a housing in which said cylinder is mounted, pin-tumblers also mounted in said housing at one side of said cylinder 30 so as to clear the leaves impaled upon said

transverse telescopic rods, springs for said tumblers, and a key removably fitted in said cylinder for releasing said tumblers and turning said cylinders, said housing being supported upon one of said guiding members 35 upon one end of said frame, and the head of said cylinder being within the contour of the frame.

6. The combination of sheet-impaling means; sheet-clamping means; a rotary shaft 40 to actuate the clamping means; a lug upon said shaft; a rotary body adjacent thereto and having a lug adapted to rotate the shaft by engagement with the lug thereon; key-controlled tumblers carried by said rotary 45 body and organized to hold a key within such body during the rotation thereof, except at one point in its rotation, the organization of the lugs upon the shaft and said body being such that after the sheets have been clamped 50 to the desired pressure the said rotary body may be idly rotated backward to the point for the removal of the key.

Signed at Nos. 9 to 15 Murray street, New York, N. Y., this 20th day of June, 1903.

THOMAS A. GLENDINNING.
